UNITED STATES PATENT OFFICE.

LOUIS A. GRAHAM, OF EVANSTON, AND CHARLES L. LOW, OF CHICAGO, ILLINOIS.

SIGN-COMPOSING DEVICE.

Application filed May 16, 1924. Serial No. 713,678.

To all whom it may concern:

Be it known that we, LOUIS A. GRAHAM and CHARLES L. Low, citizens of the United States, residing, respectively, at Evanston, in the county of Cook and State of Illinois, and at Chicago, in the county of Cook and State of Illinois, have jointly invented certain new and useful Improvements in Sign-Composing Devices, of which the following is a specification.

This invention relates to a device by means of which letters, figures, characters, or other indicia expressive of a sign or other announcement to be made, can be composed at will by selected collocation of light-affecting bodies, such as marbles, beads, or other segregated objects of spherical or other form having the capacity for transmitting, reflecting, or otherwise affecting light in contrast with a ground or field developed by a backing or mounting constructed to receive and hold them in positions in which they are placed; and particularly to a device in which the elemental characters of the sign are themselves composed by selected arrangement of the light-affecting bodies, as distinguished from composition of words or the complete sign by association of originally complete letters or the like, and, to which end, the mounting upon which the constituent objects are assembled has substantially the entire area of its field of composition formed with symmetrically disposed pockets or recesses for the objects, so that the same original segregated light-affecting objects may be employed for delineating any character desired, and in addition thereto, the background or field with which the composed characters are to contrast can be supplied with light-affecting objects of a contrasting kind, or be left with the inherent light-affecting quality of the mounting unchanged.

In carrying out the invention, the mounting in which is formed the field of pockets or seats for the composing elements is preferably constructed to pass light through it, and, to this end, it may be made of translucent material, in which case it is preferably caused to lend special character to the light that passes through it or is reflected from it, as, for instance, by making it of milk white glass or glass suitably tinted or colored; or it may be made of non-translucent material provided with perforations

sufficient in number to develop an illuminated field, the light openings being preferably coincident with the pockets for the composing objects; or the mounting may embody as its field of positioning pockets and light transmitting openings, any suitably reticulated structure, such, for instance, as woven wire.

In all forms of the invention a confining plate is laid over the composing objects to retain them in their seats, and this confining plate is rendered transparent either by making it of inherently transparent material or by providing it with apertures coincident with the composing objects to be disclosed. Moreover, this confining plate may be formed with registering pockets that receive and assist in locating the composing objects, or it may have a plane face opposed to said objects, and the backing member and confining plate may be held in assembly in any suitable manner, as, for instance, by applying to marginal portions thereof clamps, channels, frames, or the like.

In the accompanying drawing—

Figure 1 represents, in front elevation, a device embodying the several features of the invention.

Figure 2 is a vertical transverse section on an enlarged scale of a portion of the device shown in Figure 1.

Figure 3 is a fragmentary face view of the backing member of Figures 1 and 2.

Figures 4, 5, and 6 are views corresponding to Figure 2, showing modified constructions of backing member and confining plate.

Referring to Figures 1 to 3, 1 represents a backing member which, in this instance, is made of milk white translucent glass molded with symmetrically disposed seats or pockets 2 for the reception of spheres 3 of glass or other material adapted to affect light, either transmitted or reflected, and 4 represents a confining plate adapted to be placed over the objects 3 after they have been selectively located in their pockets 2 to render them definitive of elements employed for expressing a sign, notice, or the like. The 105 backing member 1 and the confining member 4 may be held in assembled relation by clamping channels 5 applied to the ends thereof, which clamping channels may serve as the means for suspending or otherwise 110 supporting the composite sign produced.

As suggested in Figure 2, the backing

member 1 may be produced as a plate of substantially uniform thickness, but with its pockets developed by alternate concave and convex portions, with the concaves on one side corresponding to the convex portions on the other side. Certain advantageous light effects will result from this particular form of backing member since refraction due to the concavo-convex portions of the plate will result in a measurably advantageous concentration of light on the composition objects.

According to Figure 4, the backing member 1^a is plane on one side and undulated on the other side to produce spherical pockets 2^a, and the confining plate 4^a is similarly constructed, so that it assists in holding the composition objects against displacement.

Figure 5 shows a mounting for the composition objects, consisting of a plate 1^b having apertures 2^b in which the composition objects 3 are seated, the confining member 4 being a plane glass plate, as in Figures 1 and 2. The apertured plate 1^b may be of glass or even opaque material since light would be transmitted through its apertures 2^b whether they are occupied by translucent composition bodies 3 or left open.

According to Figure 6, the packing member 1^c consists of a metal plate having flanged openings 2^c struck up therein, and

the confining plate 4^c is of similar construction, although it might obviously be similar to that shown in either Figure 2 or Figure 4.

35

We claim:

1. A sign composing device, comprising a mounting constructed to provide a field of symmetrically disposed seats or pockets, the field and pockets being translucent, and a plurality of light-contrasting translucent objects adapted to be selectively located in said pockets in a manner to delineate, by their comparative light transmission, characters to be expressed.

2. A sign composing device, comprising a body of translucent glass having formed therein a field of symmetrically disposed depressions, and a plurality of objects of contrasting translucency adapted to be selectively located in said pockets in a manner to delineate, by composition, characters to be expressed; and a confining plate for holding the composition objects in position, constructed of a material which passes light to both the field and the objects and renders visible the composed characters by their contrast with their surrounding field.

Signed at Chicago, Illinois, this 8th day of May, 1924.

LOUIS A. GRAHAM.
CHARLES L. LOW.
